John J. Ghegan

UNITED STATES PATENT OFFICE.

JOHN J. GHEGAN, OF EAST ORANGE, NEW JERSEY.

MORSE TRANSMITTING-KEY.

1,202,179.

Specification of Letters Patent. Patented Oct. 24, 1916.

Application filed December 15, 1915. Serial No. 66,894.

To all whom it may concern:

Be it known that I, JOHN J. GHEGAN, a citizen of the United States, residing in East Orange, in the county of Essex and 5 State of New Jersey, have made certain new and useful Improvements in Morse Transmitting-Keys, of which the following is a specification.

This invention relates to Morse transmitting keys for use with wireless telegraph apparatus, in which use a strong current is made and broken to form the Morse code; 10 sparking results and the contacts or abutting surfaces become fretted and worn, so that 15 they do not retain their normal parallel relation.

The object of my improvement is to provide adjustable removable contacts for both the anvil or lower contact and the complementary or upper contact, so that, no matter how much worn, the full contact surface can be maintained between the two contacts, and the lever always retains its normal, horizontal position. I mount the upper 20 contact on an adjustable screw, with set nut; and the lower or anvil contact is adjustable as regards the plane of its contact surface and renewable. By loosening the anvil and 25 pressing down on the key lever the two contacts, having extended area, are given perfect surface alinement; the anvil is then fixed firmly in position until wear makes a new adjustment or renewal desirable. This 30 obviates "fading" or variation in strength 35 of signals due to varying resistance at the contacts, and the contacts may be practically entirely worn out before renewal is necessary.

The key lever is a straight-line, spring- 40 retracted lever, and its free end controls the movement of a right-angled lever pivoted at the angle; the lever is spring-retracted to close a break point, and to avoid chattering the spring is connected to a point 45 in the vertical arm of the lever and to a fixed point below, in a parallel plane, closely adjacent to the plane in which the vertical arm normally rests. The free end of the 50 key lever engages the short arm of the angle-lever and this frees the key-lever of the weight of an auxiliary contact. This auxiliary contact is connected in circuit to shunt the receiving apparatus when the key 55 is depressed to transmit code signals, thus constituting a "break-in key."

In the drawing, Figure 1 is a side eleva-

tion of the improved key; Fig. 2 is a schematic diagram of a wireless telegraph transmitting and receiving circuit with the key including break-in connections. Fig. 3 60 is a top plan view and Fig. 4 is an elevation, partly in section, with screw posts removed to more clearly show essential parts.

The key lever *k* is fixed on an arbor *b* in bearings in posts *p*. The circuit breaking 65 contacts, that is, the anvil 12 and complementary contact 11, are of large superficial area on their meeting surfaces; these surfaces are liable to deterioration from sparking and fretting or continual hammering 70 in normal operation, this is due to use with a dynamo *g* and coil 40, in circuit with which the key is used. The contact 11 is supported on a screw 30 passing through lever *k*, equipped with set screw 31, as 75 shown.

The anvil contact 12 is adjustable and removable for renewal; it is screw-threaded at 18; a globular-headed screw 15 is connected with anvil contact 12 and is fixed in 80 a socket 16, in a block 13, fixed to the base *x*. A ring 14, screw-threaded on its interior at 19, engages the exterior screw-thread 17 on the block 13 fixed to the base and the cavity in ring 14 conforms to the globular 85 screw-head 15, like a ball and socket joint. The anvil contact 12 is screwed on to screw 15 after screw 15 has been passed through ring 14, ring 14 is then screwed on to block 13 which clamps anvil 12 into any position 90 desired to bring the surface of anvil 12 into parallelism with the abutting surface of contact 11. It results from this that when the abutting surfaces of contacts 11 and 12 95 are out of parallel contact 12 may be loosened in its support, key lever *k* is then depressed, forcing the surface of angle 12 into a parallel plane and the two contact surfaces are brought into complete engagement or contact at all points. When this 100 adjustment is made, the ring 14 is tightened up by the pin *y* which is carried in a perforation in post *p* until needed for use. The key lever *k* has the usual arrangement of backstop *m*. The key *k* operates an 105 auxiliary contact lever *n*, composed of two arms 20, 21, fixed at a ring angle, and pivoted at 22 to post 23, located on base *x*. Lever *n* carries contact point 28 in line with a complementary contact 29 adjustably supported in a post *r*. A spring 25 110 has one end fixed to arm 20 at 24 at a point

auxiliary contact lever *n*, composed of two arms 20, 21, fixed at a ring angle, and pivoted at 22 to post 23, located on base *x*. Lever *n* carries contact point 28 in line with a complementary contact 29 adjustably supported in a post *r*. A spring 25 110 has one end fixed to arm 20 at 24 at a point

near contact 28; the other end of spring 25 is connected to spindle 27 in post *r* in a plane parallel to arm 20 and below point 24. This arrangement I have discovered to be advantageous in preventing chattering at contacts 28, 29, and greatly superior to any other known arrangement. There is a block of insulating material *i*, like hard rubber, fixed to the terminal of lever *k* and engaging arm 21 of angular lever *n*. It results from this arrangement that when lever *k* is retracted by spring *s* and its circuit open at 11, 12, lever *n* is retracted against the effort of spring 25 and its circuit open at 28, 29.

The screw posts 60 and 61 are used for the circuit terminals of contacts 28 and 29. Screw posts 62 and 63 are used for the circuit terminals leading to contacts 11 and 20 12. The flat spring-metal connection 64 connects posts 62 with the key-lever *k*.

In Fig. 2 there is an alternating current generator *g*, the key *k* and the primary coil 40 of an inductorium, the secondary coil 25 41, shunted by condenser *c*, a spark gap *e* and adjustable primary coil *d* in the closed transmitting circuit; the secondary coil *g* is in the aerial circuit. There is also shown a receiving circuit containing primary coils 30 51 shunted by adjustable condenser 50 connected to the aerial circuit upon opposite sides of a break *h* in the aerial. In the closed receiving circuit there is an adjustable induction coil secondary 52, also used as an inductance; coil 52 is adjusted by moving pivoted arm 53 on to the series of coil-section contacts 54; in this receiving circuit there is a condenser *f*, a crystal detector *j* in shunt connection to telephone *t*, all as is well 40 known in the art.

When key *k* is depressed it closes circuit of generator *g* at points 11, 12, and releases lever *n* so that its spring 25 draws contacts 28 and 29 together, shunting the break *h* 45 via conductors 70 and 71, and also shunting coil 51 of the receiving circuit, relieving the receiving circuit more or less from the effect of the transmitted impulses. It is well known that the individual elements of this receiving circuit, or any of them, may also, if deemed desirable, be open-circuited and shunted by electromagnetic circuit-breakers or switches, as shown in patents issued to Shoemaker, to Butcher and others.

50 When contacts 11 and 12 become impaired or injured in use and it becomes necessary to polish or replace anvil contact 12, said anvil contact 12 is loosened and polished, and while loose and movable in its support

key lever *k* is depressed forcing anvil contact 12 to assume a position with its surface parallel with the plane of the surface of contact 11, whatever the position of contact 11 may be. 60

What I claim is: 65

1. The combination, in a Morse-transmitting key, of a pair of contacts, one of said contacts consisting of a plane-surfaced, screw-threaded button, a round-headed screw therefor, a fixed base-piece having a 70 socket for the screw-head, and a perforated, screw-threaded ring, the diameter of the perforation being greater at one surface than at the other.

2. The combination, in a Morse-transmitting key, of a movable contact and a complementary contact, the latter screw-threaded, a round-headed screw therefor, a fixed socket for said screw-head, and means to clamp said screw at any angle, consisting 80 of a ring adapted to engage both the screw-head and socket.

3. The combination, in a Morse-transmitting key, of two contacts, one of which has a globular terminal, a fixed base-piece having 85 an aperture conforming to said terminal and a screw-threaded ring adapted to engage said globular terminal and said base-piece and clamp said terminal in position.

4. The combination, in a Morse-transmitting key, of two contacts, one of which has one member of a universal joint, a fixed base-piece having the second member of said universal joint, and a screw-threaded ring adapted to engage both said members and 95 clamp them in set position.

5. The combination of a Morse-transmitting key having a pivoted, auxiliary lever mechanically engaging therewith, said lever having two arms united and pivoted at a 100 right-angled junction point, a contact point on one of said arms, a fixed contact point therefor, and a spring attached to said lever at or near said contact point and to a fixed point supported on the key-base, both said 105 contact points and said spring being located in the same plane.

6. The combination of a Morse-transmitting key having a pivoted auxiliary lever mechanically engaging therewith, said lever having two arms united and pivoted at a 110 right-angled junction, a contact point on one of said arms, a fixed contact point therefor, and a spring attached to said lever at or near said contact point and to a fixed 115 point supported on the key-base.

JOHN J. GHEGAN.
